(57) **CLAIM**

The ornamental design for a kickboard, as shown.

DESCRIPTION

FIG. 1 is a perspective view of the kickboard in accordance with our design.

FIG. 2 is an elevational view of the front side of the kickboard.

FIG. 3 is an elevational view of the rear side of the kickboard.

FIG. 4 is a top plan view of the kickboard.

FIG. 5 is an elevational view from the left side of the kickboard of FIG. 1.

FIG. 6 is an elevational view of the right side of the kickboard of FIG. 1; and,

FIG. 7 is a bottom plan view of the kickboard.

The evenly broken lines are included for the purpose of illustrating environmental structure and form no part of the claimed design.
